CLAIM

The ornamental design for an LED troffer light fixture, as shown and described.

DESCRIPTION

FIG. 1 is a bottom perspective view of a first embodiment of the LED troffer light fixture in accordance with the new design;

FIG. 2 is a bottom view of the first embodiment;

FIG. 3 is a top view of the first embodiment;

FIG. 4 is a right side view of the first embodiment;

FIG. 5 is a left side view of the first embodiment;

FIG. 6 is a front elevation view of the first embodiment;

FIG. 7 is a back elevation view of the first embodiment;

FIG. 8 is a bottom perspective view of a second embodiment of the LED troffer light fixture in accordance with the new design;

FIG. 9 is a bottom view of the second embodiment;

FIG. 10 is a top view of the second embodiment;

FIG. 11 is a back elevation view of the second embodiment;

FIG. 12 is a front elevation view of the second embodiment;

FIG. 13 is a right side view of the second embodiment; and,

FIG. 14 is a left side view of the second embodiment.

The broken lines present in FIGS. 1-14 illustrate portions of the LED troffer light fixture that form no part of the claimed design.
